DESIGN FOR A SCAFFOLD END FRAME

Reinhold A. Uecker, David E. Beatty, and Ingard G. Rambo, Wauwatosa, Wis., assignors to The Safway Steel Scaffolds Co. of Wisconsin, Wauwatosa, Wis., a corporation of Wisconsin

Application March 3, 1939, Serial No. 83,312

Term of patent 14 years

To all whom it may concern:

Be it known that we, Reinhold A. Uecker, David E. Beatty, and Ingard G. Rambo, citizens of the United States and residents of Wauwatosa, county of Milwaukee and State of Wisconsin, have invented a new, original, and ornamental Design for Scafford End Frames, of which the following is a specification, reference being had to the accompanying drawing, forming a part thereof.

In the drawing:

Fig. 1 is a front elevational view of a scafford end frame showing our new design;

Fig. 2 is a side elevational view of the end frame shown in Fig. 1; and

Fig. 3 is a top view of the scaffold shown in Figs. 1 and 2.

We claim:

The ornamental design for a scafford end frame, as shown.

REINHOLD A. UECKER.
